Primary Examiner — George D. Kirschbaum*Assistant Examiner* — Maria J Edwards(74) *Attorney, Agent, or Firm* — Porzio Bromberg & Newman P.C.(57) **CLAIM**

The ornamental design for a protective sleeved glove, as shown and described.

DESCRIPTION

FIG. 1 is a top and side view of a right hand protective glove showing our new design,

FIG. 2 is a bottom view thereof,

FIG. 3 is a top view thereof,

FIG. 4 is a first side view thereof,

FIG. 5 is a second side view thereof,

FIG. 6 is a first end view thereof; and,

FIG. 7 is a second end view thereof.

The broken lines in FIG. 7 form a boundary of the claim and form no part of the claimed design.

1 Claim, 4 Drawing Sheets(56)
